PICTORIAL DISPLAY DEVICE

Lini Allen, Berkeley, Calif.

Application September 25, 1945, Serial No. 618,503

2 Claims. (Cl. 35—1)

1

The present invention relates to a pictorial display device, and more particularly to a seasonal novelty for children by which interest, anticipation and surprise in certain coming events may be progressively built up.

An object of the invention is to provide a novelty for use during seasonal periods of the year to stimulate a child's interest in a coming event.

Another object of the invention is to provide a pictorial display device having manipulatable parts which, when operated, will successively reveal material in the form of pictures or script that is symbolic of a particular date during the period covered by the device.

In the development of a child's education, one of the most satisfactory methods is to associate an idea with a picture or verse pertinent thereto, and when the idea of time and events is involved, a better understanding of the significance and spirit of a holiday season or historical event may be effectively presented in an interesting manner by association with particular dates. It is, therefore, a further object of the invention to provide a calendar-like novelty having manipulatable parts in association with pictures, verses and/or other intelligence-conveying means in a manner that will stimulate interest and impress the mind of a child.

Other objects and advantages of the invention will be in part evident to those skilled in the art, and in part pointed out hereinafter in the following description taken in connection with the accompanying drawing, wherein there is shown by way of illustration and not of limitation preferred embodiments of the invention.

In the drawing:

Figure 1 is a fragmentary view showing the front face of a pictorial display device constructed in accordance with the invention.

Figure 2 is a fragmentary view showing another portion of the device of the type contemplated by Figure 1.

Figure 3 is a slightly enlarged fragmentary view showing in more detail a portion of the device illustrated in Figure 1 of the drawing.

Figure 4 is a fragmentary front view of a device constructed in accordance with the invention and embodying a different design, and

Figure 5 shows a novelty of the latter type, completed and having a suitable supporting frame by which it may be hung from a wall or other support.

Graphic displays made in accordance with this invention may be associated with any particular season or historical event by merely arranging the physical features to conform with the ornamentation or design which may be reproduced on the face thereof. In Figure 1 there is illustrated a seasonal display device which is particularly adapted for use during its Christmas season, and

2

in conformity therewith the ornamentation upon the face includes the outline of a chalet having balconies and a plurality of shuttered windows. The chalet is pictured upon a relatively stiff member 10 of cardboard or other like material which will form the front of a display unit. With such a design, where the windows of the chalet appear, the member 10 is cut so as to form hinged portions 11 that may be turned outwardly to expose to view any illustration or other matter which may be in register therewith. In addition to being hinged, the portions 11, when closed, are adapted to carry numbers on their exposed sides corresponding with the dates of a particular month or season. In the present instance the device is designed for the Christmas season and, therefore, the dates are only carried up to and including the 25th of the month, which is Christmas Day. Arranged behind the front portion 10 there is a second sheet-like member 12 upon which there are provided spaced areas 13 having symbols, pictures of articles and/or verses which are positioned thereupon in such a manner that they will each register with a window of the chalet and thus come into view as the dated hinged portions 11 are successively turned outwardly during the course of the period involved. In this showing the member 12 carries illustrations of articles that might be considered suitable presents for different members of a family. In this connection it might be added that in this manner the displays may be made up for acceptance by different age groups merely by varying the nature of the illustration or verses carried by the areas 13 of the member 12. For example, the member 12 may carry illustrations of presents that would be desired by boys or girls and of different ages. Likewise, if the device is to cover the Easter season, the areas 13 of the member 12 may be provided with appropriate biblical verses.

As is more clearly indicated in Figure 3 of the drawing, when the parts 10 and 12 have been assembled in this manner, it will be possible for 45 the child to turn out the hinged portions 11 of the front portion 10 on the dates of the month carried thereby and thus daily bring into view the symbols, illustrations and/or other material carried by the areas 13 of the member 12 and 50 thus bring to mind gifts desired by the individual or which may be given to another. For example, in the instance illustrated, by opening the hinged portion 11 carrying the first date of the month, here shown as applied to the door of a doghouse, the child will expose to view a pair of skates as a possible Christmas present. In the same manner, by opening the hinged portions 11 carrying the second date of the month, there would be revealed a bookcase with books, or a comparable article that might also be a present in contem-

plation. Likewise, when the hinged portions 11 carrying the fifth date of the month are opened, there might be revealed a wrist watch which will bring to mind a gift for dad or some other member of a family.

In Figure 4 of the drawing there is shown an alternative design for a Christmas novelty in which a front cover portion, designated by the numeral 14, is colored and ornamented to depict a conventional Christmas tree upon which there is blocked out twenty-five rectangular areas that carry the respective dates of the month up to and including the 25th, or Christmas Day. In this instance the portion 14 is cut at these several rectangular areas so as to provide outwardly swinging hinged door-like portions 15 that may be swung outwardly to expose pictures, symbols and/or verses carried by a second member 16 which is positioned therebehind. The pictures, symbols or other matter upon the member 16 are likewise arranged to register with the date-carrying rectangular areas of the member 14, as above indicated in connection with Figure 2 of the drawing. In this instance the hinged door-like portion 15, which carries the 12th date of the month, when opened, is shown as exposing a spinning top which may be suitable as a gift for a small boy. Likewise, the hinged members 15, which carry the 23rd date of the month, when swung out as here shown, will reveal a different toy, here illustrated as a scooter. In like manner all of the hinged portions 15 will reveal different toys when opened on successive dates.

From the above it will be seen that the size and shape of the front and back portions of the device will be such as to conform with the ornamentation appearing upon its front portion 10 of the calendar, and to complete the assembly, if desired, these two members, when properly associated with each other, may be firmly secured together with a suitable adhesive or, in a more elaborate arrangement, the device may be provided with a frame 17, as indicated in Figure 5 of the drawing.

As a further modification, it is also contemplated that the completed novelty, having sufficient numbered areas to cover a full month, may be provided with a number of separate back forming portions 12, having different symbols or illustrations, that may be substituted for each other on successive years. In a like manner, the several back portions 12 may carry symbols, verses or illustrations that would render the display suitable for different seasons of any one year. For example, if the novelty is ornamented in the manner appropriate to the Christmas season, several separately usable back portions 12 may be provided, each with illustrations that will be appropriate to the different ages of a growing child. By the same token, if a number of the back portions 12 are provided, each having illustrations in different categories, it will be possible to produce displays that may be rendered appropriate at any one time for either a boy or girl, and of varying ages, by merely substituting one for the other of these several back portions 12.

If it should be desirable to impart a toy-like characteristic to the device, the arrangement illustrated in Figure 5 of the drawing might be provided with a box-like frame 17 having a slot 18 in the top or the side thereof through which any one of a number of the members 14, carrying different symbols, pictures or verses, might be in-

dividually inserted thus to effect a change in the nature of the picture or the like which will be exposed upon a turning out of the hinged portions 15 of the member 14.

While I have, for the sake of clearness and in order to disclose the invention so that the same can be readily understood, described and illustrated specific devices and arrangements, it is to be understood that the invention is not limited to the specific forms disclosed, but may be embodied in other forms that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. A pictorial display device, intended for the progressive revelation and display of graphic representations over a pre-selected period of time in a manner combining the elements of surprise and suspense, which comprises: a planar backing element containing upon a surface thereof a plurality of divisions of graphic material of varied substance and form; a cover sheet superimposed upon said backing element so as to conceal the graphic material contained upon the confronting surface of the backing element; a plurality of viewing apertures disposed in said cover sheet in number and orientation corresponding to the underlying divisions of graphic material contained upon the backing element; a closure for each of said apertures arranged to conceal the underlying graphic material, respectively, of each of the divisions when in closed position, and to reveal said material when in open position; suitable indicia associated with each aperture and closure by which it may be identified, and by which, in relation to each other, a progressive sequence for the consecutive revelation and display of the underlying graphic material might be established; and a pictorial design upon the outer face of said cover sheet in which the apertures and closures thereof are artistically accommodated as a representational part so as to become integrated thereby into a logical association.

2. The invention recited in claim 1, in which the backing element and cover sheet are separable to allow for the substitution and association, respectively, of other conforming backing elements and cover sheets therewith to renew the displays and to vary the presentations thereof.
